MUSICAL TOY

Michael Satten, 93—25 86th Road,
Queens, N.Y. 11421

Filed Oct. 2, 1972, Ser. No. 294,338

Term of patent 7 years

Int. Cl. D21—01

U.S. Cl. D34—15 C

Fig. 1.

Fig. 2.

Fig. 3.

Fig. 4.

FIG. 1 is a perspective view of a musical toy showing my new design;

FIG. 2 is a left-side elevational view;

FIG. 3 is a front elevational view;

FIG. 4 is a top plan view.

The rear and bottom surfaces, not shown, are substantially plain and unornamented.

I claim:

The ornamental design for a musical toy, as shown and described.
